(57) **CLAIM**

The ornamental design for set of curvilinear fins for a shaving cartridge, as shown and described.

DESCRIPTION

FIG. 1 is a top-right front perspective view of the set of curvilinear fins for a shaving cartridge;

FIG. 2 is a top plan view thereof;

FIG. 3 is a front elevational view thereof;

FIG. 4 is a bottom plan thereof;

FIG. 5 is a rear elevational view thereof; and,

FIG. 6 is a right-side elevational view thereof, the left-side elevational view being a mirror image thereof.

The broken lines illustrate the environment and form no part of the claimed design.
